(57) CLAIM

The ornamental design for an article of jewelry, as shown and described.

DESCRIPTION

FIG. 1 is an environmental front elevational view of an article of jewelry showing my new design; FIG. 2 is a front elevational view thereof; and, FIG. 3 is a rear elevational view thereof.

The broken line showing of words in FIG. 1 is for illustrative purposes only and forms no part of the claimed design. It being understood that the broken line showing of words in FIG. 1 and a chain in FIGS. 1-3 is for illustrative purposes only and forms no part of the claimed design.
